THREAD FEED STOPPING DEVICE

Heinz Bade, Hamburg, Germany, assignor, by mesne assignments, to Messrs. James Mackie & Sons Limited, Belfast, Northern Ireland

Application January 8, 1954, Serial No. 403,014.

Claims priority, application Germany January 10, 1953

10 Claims. (Cl. 57—83)

The invention relates to a device for automatic interruption of the supply of spinning material to spinning machines, in particular jute spinning machines, upon breaking of the fibre or thread, through the actuation of a feeler lever and rotating arresting pawl substantially as disclosed in my prior Patent No. 2,623,348, dated December 30, 1952.

For this purpose it has already been proposed to arrange between the driven feed roller and an impact ring controllable by a thread feeler, both of which are freely mounted on the driving shaft, an intermediary member surrounding the said driving shaft, which member is permanently in engagement with the feed roller and with the impact ring and which effects a friction coupling between the feed roller and the driving shaft as soon as the rotation of the feed roller lags behind the driving shaft.

In particular for carrying out this general idea a spiral spring surrounding the shaft is connected on the one hand to the one end of the driven feed roller and on the other hand to the impact ring.

According to the invention the intermediary member comprises a spring ring of preferably rectangular cross section, which at that side which faces the driving shaft is provided with a cavity which is of wedge shape with respect to the surface of the shaft, which cavity lies opposite to a recess provided at the opposite side of the spring ring for allowing resilient movement thereof; also between the said wedge shaped cavity and the shaft there is provided an annular space in which is positioned a rolling member, and into which projects a collar connected fast to the impact ring in such a manner that the rolling member lies in a gap formed by interrupting the said collar. This arrangement results in an extremely simple construction in that a wound spring ring need not be used but merely a resilient steel ring which can deflect in a cavity. The coupling and de-coupling may be carried out in a very reliable manner with very simple means.

Preferably the wedge shaped cavity is so formed that in the rest position of the intermediary ring there exists a minimum value for the interval between the wedge surface and the driving shaft, which minimum value is less than the diameter of the rolling member, and from this position the wedge surface is so shaped that on either side of the minimum interval the distance between the wedge surface and the driving shaft increases. By this means there is obtained the advantage that upon the occurrence of an over-load the intermediary ring yields to such an extent that the rolling member rolls away from the position of minimum interval and, since the interval between the wedge surface and the shaft increases, releases the coupling. In the practical operation of the device the fact that over-load protection is provided by the device according to the invention without breakdown of any one of the parts represents a substantial advantage.

The rolling member may be in the form of a roller or

2

a ball. The recess, which lies opposite to the wedge shaped cavity, may be formed either in the intermediary ring or alternatively in the feed roller. The intermediary ring may be in the form of a completely closed ring or a divided ring.

Further improvements and suitable embodiments of the invention will now be described with reference to the accompanying drawing in which are represented simplified constructions whilst omitting all the details which are not immediately essential.

In the drawings:

Fig. 1 is a longitudinal section through a device construction according to the invention;

Fig. 2 is a cross section through this device according to the line II—II of Fig. 1;

Fig. 3 is a longitudinal section through another form of the invention;

Fig. 4 is a cross section along the line IV—IV of Fig. 3;

Fig. 5 is a cross section along the line V—V of Fig. 3.

For a description of the further details of such a device reference may be had to the disclosure in the said prior U. S. Patent No. 2,623,348.

Upon the driving shaft 1 there are freely mounted in adjacent relationship an impact ring 2 and a feed roller 3. The impact ring is provided with a plurality of detents 6 which are preferably equally distributed around its periphery and with which detents a pawl 21, equivalent to pawl 16 of my said prior Patent No. 2,623,348, can engage, upon breakage of the thread, to arrest rotation of the impact ring. Within a concentric groove of the feed roller 3 there is arranged an intermediary ring 8 between whose two ends 9 and 10 engages a pin 11 which is secured fast to the feed roller 3. Between this intermediary ring 8 and the driving shaft 1 there is an annular space into which projects a collar 5 which is in one piece with the impact ring 2. This collar is split in such a way that it forms a cage 12 within which a roller 4 is freely rotatable. The diameter of this roller is a little greater than the thickness of the collar 5.

The intermediary ring 8 is provided at that end adjacent to its edge 9 with a wedge shaped cavity 7 which comprises a wedge surface 13 and a transitional rounded surface 14. The wedge surface 13 represents substantially a tangent at the inner periphery of the intermediary ring 8, in that at the point P there exists the minimum free space between the wedge surface 13 and the surface of the driving shaft 1. From this point outwards the distances between the wedge surface and the shaft gradually increase.

The intermediary ring is provided at its outer surface, i. e. that surface which is opposite to the wedge surface 13, with a long recess 15 which extends from the edge 9 to a point 16. The recess 15 is therefore somewhat longer than the wedge shaped cavity 7. Thus when pressure is exerted outwardly upon the wedge surface 13 the ring 8 is able to spring outwardly.

Figure 2 shows the device according to the invention in the uncoupled condition in which the roller 4 is situated in the rounded portion 14. When the impact ring 2 is not held fast by the impact lever, the said ring is carried round in consequence of the friction of the rotating driving shaft 1, whereby the roller 4 resting in the cage 12 is also carried along in the direction of the arrow a—b.

In this way there is produced a clamping action between the wedge surface 13, the roller 4 and the periphery of the driving shaft 1 so that the feed roller 3 is also driven. Upon the occurrence of an over-load and the application of a correspondingly increased moment the roller 4 is rotated past the point P of minimum interval, so that thereupon the coupling again releases due to the increase of the wedge interval.

As soon as the impact ring 2 is held fast upon actuation of the knock-off motion by means of the impact lever (not shown), then, by the overtaking action of the feed roller 3, the roller 4 rotates out of the wedge angle into the position shown in Figure 2 in which the coupling is released and in which the feed roller 3 is also locked against further rotary motion since the roller 4 lies against the rounded portion 14 of the ring 8.

A further advantage of the invention lies in the fact that it is not necessary to provide right-handed and left-handed constructions of the individual parts.

In the constructional form shown in Figs. 3 to 5 a completely closed intermediary ring is employed instead of a divided ring. Otherwise this construction corresponds substantially with that shown in Figs. 1 and 2 so that the same reference characters are used to indicate the same or corresponding parts in each construction. The pin 11 connected with the feed roller 3 is here received in an aperture 17 provided for this purpose in the intermediary ring 8. The wedge shaped cavity 7 in this case comprises a circular arcuate portion 18 whose radius is larger than that of the inner surface of the intermediary ring 8' and whose centre point lies eccentric to the axis of the shaft 1. In this manner there is formed an arcuate cavity with two wedge surfaces which meet on the point P where the width of the wedge is at a minimum. From the point P the wedge surfaces extend on both sides in such a manner that the interval between the arcuate section 18 and the periphery of the driving shaft increases.

A leaf spring 20 is inserted in an annular groove 19 of the impact ring 2 in such a manner that its ends lie against the outer periphery of the groove whilst its centre is pressed against the periphery of the shaft 1. In this manner there is obtained between the impact ring and the shaft 1 a frictional effect whose value can be accurately determined and this effect improves the mode of operation of the device, which it is not necessary to describe in further detail since it corresponds substantially with that of the device described in Figures 1 to 3.

In the construction according to Fig. 3 the recess 15 which lies opposite the wedge shaped cavity 7 is provided in the feed roller 3 without altering in any respect the mode of operation of the device.

What I claim is:

1. In a device for automatically interrupting the supply of spinning material to spinning machines in particular jute spinning machines, upon breakage of a fibre or thread, in combination, a rotatable shaft, a feed roller rotatably supported on said shaft, a detent member rotatably supported on said shaft adjacent said feed roller and provided with detents, a rotating arresting pawl actuated upon breakage of the thread to move into the path of said detents, a radially resilient spring member drivably connected with said feed roller and provided with an inclined surface wedged with respect to said detent member, a rolling member drivably connected to said detent member and engaging both said shaft and said inclined surface of said spring member, said spring member and said feed roller defining between them a space opposite to said inclined surface.

2. In a device as claimed in claim 1, a collar connected with said detent member and having a cage for receiving said rolling member, said feed roller having a recess therein for receiving said collar.

3. In a device as claimed in claim 1, said spring member having a cavity and said feed roller being provided with a protruding member engaging in said cavity.

4. In a device as claimed in claim 1, said spring member being formed as a ring divided by a gap for receiving a protruding member provided on said feed roller, said inclined surface being provided on one free end of said ring-formed spring member.

5. In a device as claimed in claim 4, said ring-formed spring member being provided with a long recess opposite to said inclined surface.

6. In a device as claimed in claim 1, said inclined surface forming substantially a tangent with respect to a circle having its centre on the axis of said shaft.

7. In a device as claimed in claim 1, said inclined surface following a circle the centre of which is eccentric with respect to the axis of said shaft.

8. In a device as claimed in claim 1, resilient means being provided between said detent member and said shaft for increasing the frictional resistance between said member and said shaft.

9. In a device for automatically interrupting the supply of spinning material to spinning machines in particular jute spinning machines, upon breakage of a fibre or

25 thread, in combination, a rotatable shaft, a feed roller rotatably supported on said shaft, a detent member rotatably supported on said shaft adjacent said feed roller and provided with detents, a rotating arresting pawl actuated upon breakage of the thread to move into the path of said detents, a closed ring drivably connected with said feed roller and encircling said shaft, a double-wedged surface provided on the inner side of said ring, said closed ring and feed roller having a space between them opposite said double wedged surface, a rolling member engaging 30 both said double-wedged surface and said shaft, a collar connected with said detent member and having a cage for receiving said rolling member, said feed roller having a recess therein for receiving said collar.

10. In a device for automatically interrupting the supply of spinning material to spinning machines in particular jute spinning machines, upon breakage of a fibre or

35 thread, in combination, a rotatable shaft, a feed roller rotatably supported on said shaft, a detent member rotatably supported on said shaft adjacent said feed roller and provided with detents, a rotating arresting pawl actuated upon breakage of the thread to move into the path of said detents, a closed ring drivably connected with said feed roller and encircling said shaft, a double-wedged surface provided on the inner side of said ring, said closed ring and feed roller having a space between them opposite said double-wedged surface, a rolling member engaging 40 both said double-wedged surface and said shaft, a collar connected with said detent member and having a cage for receiving said rolling member, said feed roller having a recess therein for receiving said collar.

11. In a device for automatically interrupting the supply of spinning material to spinning machines in particular jute spinning machines, upon breakage of a fibre or

45 thread, in combination, a rotatable shaft, a feed roller rotatably supported on said shaft, a detent member rotatably supported on said shaft adjacent said feed roller and provided with detents, a rotating arresting pawl actuated upon breakage of the thread to move into the path of said detents, a closed ring drivably connected with said feed roller and encircling said shaft, a double-wedged surface provided on the inner side of said ring, said closed ring and feed roller having a space between them opposite said double-wedged surface, a rolling member engaging 50 both said double-wedged surface and said shaft, a collar connected with said detent member and having a cage for receiving said rolling member, said feed roller having a recess therein for receiving said collar.

12. In a device for automatically interrupting the supply of spinning material to spinning machines in particular jute spinning machines, upon breakage of a fibre or

55 thread, in combination, a rotatable shaft, a feed roller rotatably supported on said shaft, a detent member rotatably supported on said shaft adjacent said feed roller and provided with detents, a rotating arresting pawl actuated upon breakage of the thread to move into the path of said detents, a closed ring drivably connected with said feed roller and encircling said shaft, a double-wedged surface provided on the inner side of said ring, said closed ring and feed roller having a space between them opposite said double-wedged surface, a rolling member engaging both said double-wedged surface and said shaft, a collar connected with said detent member and having a cage for receiving said rolling member, said feed roller having a recess therein for receiving said collar and a second recess therein opposite to said double-wedged surface of said ring.
